COMBINED MUSIC BOX AND TOTE BOX OR THE LIKE

Ernest L. Thornell, Horicon, Wis., assignor to Marlin Toy Products Inc.

Filed Mar. 2, 1970, Ser. No. 21,691

Term of patent 14 years

Int. Cl. D3—01

U.S. Cl. D87—1

FIG. 1 is a perspective view of a combined music box and tote box or the like embodying my new design;

FIG. 2 is an end elevation of the same;

FIG. 3 is a top plan view of the same;

FIG. 4 is a bottom plan view of the same;

FIG. 5 is a perspective of the same in opened condition.

I claim:

The ornamental design for a combined music box and tote box or the like, as shown.
